CARRY BAG WITH BRIDGING STRIP

George W. Poppe, Brooklyn, N. Y., assignor to
 Equitable Paper Bag Co., Inc., Brooklyn, N. Y.,
 a corporation of New York

Application May 5, 1934, Serial No. 724,144

3 Claims. (Cl. 93—35)

This invention relates to a carry bag and the method of making the same and one of its objects is to produce a carry bag in which a minimum amount of paper is used consistent with the necessary strength.

Another object is the production of a bag of this type by methods adapted for use with ordinary bag machinery and at the same speed with which ordinary bags are produced.

10 In my application Serial No. 724,143, filed May 5, 1934, I have disclosed a method of forming a tab or tongue on a bag lip which tongue is of the same width as the overlapped seam of one of the bag walls. In the making of the bag by the method described in said application, reenforcement of the tab is brought about by reason of the overlapped seam. In such bag, however, where additional strength is found to be necessary, a re-enforcing strip has been used which is secured 15 to the front bag wall. This bag wall is therefore of double thickness and an additional amount of paper is required for its manufacture.

In the present invention, however, no more paper is required than in making an ordinary bag 20 and the reenforcement of the tab or tongue and the reenforcement of one of the bag walls through which the tab passes to form a finger hold for carrying the bag may be made as heavy as desired.

30 An important feature of the invention, therefore, is the use of a bridging strip of heavier material than the material out of which the rest of the bag is formed, the aperture in one bag wall passing substantially midway of the strip; the tab likewise being cut into the edges of the bridging strip.

A further feature of the invention resides in the manner by which the tab is cut. In my Patent 1,895,267, January 24, 1933, I have shown a 40 carry bag in which the walls are widely overlapped and the tab is cut out of the seam within the paste lines. Considerable more paper is required in the making of such a bag than in the making of the present bag. Furthermore, in the bag of my said patent the tab is cut after the bag has been severed from the tube.

45 A further feature of the present invention, therefore, resides in cutting slits in the bridging strip prior to pasting said strip to the main bag web to form a tube, said slits being spaced apart a distance equal to the width of the tab.

50 The invention will be better understood by reference to the following description and accompanying drawings in which

Figure 1 is a front view of a bag of the present invention;

Figure 2 is a view of the opposite side of the bag shown in Figure 1;

Figure 3 is a section on the line 3—3, Figure 1;

Figure 4 is a top plan view illustrating the manner of folding the main web and feeding the bridging strip or web thereto;

Figure 5 is a section on the line 5—5, Figure 6;

Figure 6 is a section more or less diagrammatically shown of an ordinary bag machine modified in a manner to practice the method of my present invention; and

Figure 7 is a view looking in the direction of the arrows along the line 7—7, Figure 6.

Referring to Figures 1 and 2 of the drawings, 1 indicates the front wall of my improved bag, which bag is formed by folding a web into a tube but the edges of the web do not overlap, the edge 2, as shown more particularly in Figure 3, being 20 spaced from the edge 3. The edges of the web, however, are bridged by a strip or web 4 overlapping the edges 2 and 3 and secured to the main web by lines of paste 6 and 8. As illustrated in Figure 3, the bridging strip 4 overlaps the 25 main web on the outside but it is obvious that said strip might just as well overlap on the inside. Either construction is within the scope of my invention.

The bag is provided with a closing lip or flap 10 which is a prolongation of the rear wall of the bag and into the edges of this flap and approximately centrally of the bridging strip I form a tab 12 by slits 14 and 15. When the lip 10 is folded down on the wall 1, the tab 12 is adapted to pass through an aperture 16 in the front bag wall and a superposed aperture 17 in the rear wall, the aperture 17 being within the side edges of the strip 4. It will be apparent that such a bag requires no more paper than an ordinary bag having a central overlapped seam in its rear wall. The advantage, however, of the present bag resides in the fact that notwithstanding the economic use of paper the strip 4 40 may be made of material substantially heavier than that required for the rest of the bag and therefore the tab 12 which is formed in this heavier paper forms a very substantial means by which the bag may be carried.

The process by which the bag hereinbefore described may be conveniently produced is illustrated in Figures 4 to 7, inclusive, and since the bags of this type would in practice be produced by machinery, I have illustrated a conventional 50

bag machine by way of more conveniently setting forth the method.

Referring to Figure 6, I have shown more or less diagrammatically the essential elements of 5 a conventional bag machine and have illustrated one way in which such machine may be modified in order to illustrate my improved method of producing the bag illustrated in Figures 1 and 2. For a more detailed showing and description of 10 the operation of such machine, reference is made to my Patent No. 1,943,549, granted January 16, 1934.

Before describing in detail the instrumentalities which may be practically employed in the 15 carrying out of my method it may be stated by way of introduction that the method consists broadly in folding a web of the paper to form a bag tube, the edges of the web after folding being spaced apart, bridging such space by a web 20 which is secured at its edges to the separated edges of the folded web and subsequently severing the tube into bag lengths.

I do not wish to limit myself to the particular 25 way illustrated by which the bridging web is brought into proper registry with the folded over edges of the main web, since such registry may be effected in different ways. For the purpose, however, of illustrating one practical embodiment of the method, reference is made to Figure 6.

30 The various shafts are driven in a manner well-known in the bag machine art as more particularly set forth in my Patent No. 1,943,549, above referred to.

The paper forming the main web 20 is fed from 35 a roll of paper 22 and passes over suitable guide rollers to a roller 24 which reverses its direction of movement. The web, after passing the roller 24, is fed under a former 26 about which it is folded to form the bag tube. The beginning of 40 the fold is shown at 21, Figures 4 and 6.

In the practice of my improved method, however, the edges of the webs 2 and 3, Figure 4, are not overlapped to form a bag seam as is customary in the making of an ordinary bag 45 but on the contrary the web is folded in such a manner that said edges are spaced apart so that a narrower web of paper than would be necessary in the making of an ordinary bag may be used. However, in order to complete the bag wall I feed 50 in an auxiliary web or bridging strip 4 of heavier paper than that used for the rest of the bag and secure it to the separated edges of the main web. This auxiliary strip 4, as shown in Figure 55 6, is fed from a roll 28 supported in a bracket 30 suitably supported from the base of the machine, said strip passing over an idler 32 and over a roller 34 supported on a shaft 36 journalled in an upright 37 forming part of the machine framework. The roller 34 is preferably made of steel 60 and need not be substantially wider than the strip 4, as shown in Figure 7. The reason for this being preferably made of steel will herein-after appear.

The web, after passing over the roller 34, is 65 fed adjacent a roller 38 and near this point in its passage receives two lines of paste applied by paste discs 40 rotating in a paste-pot 42 suitably supported in the framework of the machine. The auxiliary web or strip 4 is pulled along by feed 70 rollers 44 and 45 driven from the main feed rollers 46, the latter in turn being driven from the lower pinch bar shaft 48 in the manner shown in my said patent, said pinch bar shaft being numbered 8 therein. Details of the drive of the 75 rollers 44 and 45 are shown in an enlarged view,

Figure 5, wherein a gear 49 on the shaft of the roller 45 meshes with an idler 50, Figure 6, which in turn meshes with a gear on the upper main feed roller 46. The opposite end of the shaft of the roller 45 carries a gear 52 meshing with a gear 53 on the shaft carrying the roller 44. Gear 49 meshes with the gear 54 on the same shaft. By this arrangement the rollers 44 and 45 are driven at the same peripheral speed. The feed rollers 46 are not continuous but the upper two 10 are, in fact, two rollers. It is customary to make these rollers in this manner as clearly shown in Figure 2 of my said patent. From a consideration of Figures 4 and 6 it will be apparent that the auxiliary web or bridging strip 4 is fed in juxtaposition to the main web after the same has been folded in the manner shown in Figure 4 with its edges 2 and 3 spaced apart. While I have shown the web passing on the outside of the main web, it is, of course, obvious that said web could be fed in juxtaposition to the main web prior to complete folding of the latter so that the auxiliary web or bridging strip 4 would pass underneath the edges 2 and 3 and in the finished bag said strip would be on the inside instead of the outside.

It is customary in ordinary bag machines to apply a line of paste to the main web during its passage over the roller 24. In practicing my present method I do not apply any paste to the main web 20. The bag tube is completed solely through the bridging strip 4 and the paste is applied only to it. It is obvious, however, that if the strip 4 is run on the inside the lines of paste might be applied to the main web adjacent the edges thereof but this would necessitate two paste pots spaced a considerable distance from each other. With the method described, only one paste pot is needed, since the paste lines when applied to the bridging strip need not be widely separated.

The rollers 44 and 45 act as feeding means only for the strip 4. To press the edges of the strip 4 in close contact with the edges of the main web I employ a roller 51. The tube is now 45 completely formed and is cut into bag lengths by the usual mechanism provided for this purpose. Briefly, this mechanism includes the pinch bars 55 which at the proper time retard the movement of the tube, creating the necessary slack to 50 enable it to be readily severed. This is done at the proper instant by a striker bar 58 carried by a sprocket chain 59 passing over sprockets 60 and 61 which gives a sharp blow to the under side of the tube, one wall of said tube being 55 severed by the serrated edge 62 of the former and the other or upper seam wall being severed by the serrated edge 64 of the lip knife. In Figure 6 the thickness of the several plies of paper are shown somewhat exaggerated to show the 60 construction of the tube.

The tab 12 is preferably formed by making pairs of slits at bag length intervals apart in the bridging strip 4 before the same is pasted to the main web. This may conveniently be done 65 by providing a pair of dies 66 mounted on a shaft 68 which is driven by a sprocket chain 70 driven by a sprocket 71 mounted on a shaft 72 the latter corresponding to the shaft 13, Figure 1 of my aforesaid Patent No. 1,943,549. The radial distance between the shaft 68 and the cutting edge of the dies is the same as the radius of the feed rollers 46. The diameter of said rollers 46 is such that upon each rotation thereof the web is fed 70 forward a bag length. The shaft 68 is so geared 75

that it makes one revolution with each revolution of the rollers 46. It results therefore that the dies 66 will make slits in the web 4 at bag length intervals apart.

5 The timing of the striker bar in relation to the feed rollers 46 is such that the lip knife cuts the upper bag wall along a line which meets the ends of the cuts 14 and 15 made by the dies 66 in the web 4, as clearly shown by the dotted line 13, Figure 4. The lip knife 64 has a rounded edge, thereby giving a rounded shape to the bag lip. The left hand portion, Figure 4, shows the end of the tube as having been cut off, the edge 14 indicating the cut made by the lip knife 64 while the edge 15 indicates the cut made by the edge of the former.

10 After a bag section is thus cut off, the bottom passes the mechanism (not shown) which folds and pastes the bottom in the usual and well-known way.

15 It has been previously stated that the roller 34 is preferably made of steel and the reason for this is due to the fact that the dies 66 act against this roller in cutting the slits in the web, which slits are to form the edges of the tab in the flap of the finished bag.

I claim:

1. A carry bag formed of a folded web of one weight of paper, the edges of which web are spaced apart at the rear bag wall, a bridging strip of heavier paper secured at its edges to the sepa-

rated edges of the folded web, said bridging strip running the full length of the rear bag wall, a closing flap which is a prolongation of said rear wall and a tab cut into the edge of said flap and within the side edges of said bridging strip. 5

2. A carry bag formed of a folded web of one weight of paper, the edges of which web are spaced apart at the rear bag wall, a bridging strip of heavier paper secured at its edges to the separated edges of the folded web, said bridging strip 10 running the full length of the rear bag wall, a closing flap which is a prolongation of said rear wall and a tab cut into the edge of said flap and within the edges of said bridging strip and an opening in the bag walls through which said 15 tab may be passed.

3. The method of producing a bag as defined in claim 1 which consists in folding a web of paper to form a bag tube, the edges of the web after folding being spaced apart, cutting slits in 20 a second web spaced apart a distance equal to the desired width of a tab, such slits being spaced bag length intervals apart, feeding said second web in a manner such that its edges overlap the spaced edges of the folded first web, securing 25 the second web to the edges of the first web and severing the completed tube so formed into bag lengths, the line of severance of the seam wall meeting the edges of a pair of said slits.

30
GEORGE W. POPPE.
